UNITED STATES PATENT OFFICE.

JOHN ELDON SHEPHERD, OF FLUSHING, NEW YORK, ASSIGNOR TO AUTOMATIC FIRE PROTECTION COMPANY, A CORPORATION OF MAINE.

AUTOMATIC FIRE-PROTECTION SIGNAL SYSTEM

1,056,459.

Specification of Letters Patent.

Patented Mar. 18, 1913.

Original application filed June 20, 1908, Serial No. 411,827. Divided and this application filed November 19, 1910. Serial No. 593,141.

To all whom it may concern:

Be it known that I, JOHN E. SHEPHERD, a citizen of the United States, residing at Flushing, in the county of Queens and State of New York, have invented certain new and useful Improvements in Automatic Fire-Protection Signal Systems, of which the following is a specification.

This application is a division of my prior 10 application Serial No. 411,827, filed June 20, 1908.

The invention relates to improvements in 15 automatic fire protection signal systems, and has for its general object to provide improvements applicable to systems for automatic fire alarm signaling, manual alarm signaling, or a combination of the two.

It has heretofore been to some extent the practice to provide a manual fire alarm signaling system comprising a master transmitter located at some suitable point, and connected in a signaling circuit with a supervisory station, usually at some distance therefrom, and to arrange "auxiliary" 20 boxes at different points within the area to be afforded protection, such auxiliary boxes when actuated serving merely to close an electric circuit, including master-box controlling mechanism, which, when energized, 25 serves to actuate the master transmitter, and occasion it to transmit in the signaling circuit; but such systems as heretofore practised have been open to objections in that the auxiliary circuit and boxes were not 30 under test and might be so designed as to leave the area supposedly protected without means of fire alarm transmission, without any supervising authority becoming aware of the failure of the apparatus. Furthermore, 35 it has heretofore been suggested to employ a fire detecting and signal initiating system comprising a piping installation, preferably of small diameter, containing air maintained under atmospheric pressure by 40 the relief of a constantly-open vent, such piping closed at one end and extending throughout the area to be protected and at its open end communicating with a pressure-responsive device capable of closing a 45 circuit to initiate a bell signal upon a sudden increase of pressure due to sudden heating of the piping, but such system is likewise 50 disadvantageous in that the detector

piping may be broken or cut in two, and the system rendered inoperative without the knowledge of the supervising authorities.

Among the objects of the present invention are to provide an "auxiliary box" fire alarm telegraph system in which the auxiliary circuit is under test; to provide such a system in which the failure of the auxiliary circuit will result in the initiation of a trouble-signal distinctive from a fire alarm signal; to provide supervision for the auxiliary system through the fire alarm telegraph system itself; to provide an improved and highly sensitive heat detector system and improved means for maintaining normally atmospheric pressure within the system at all times while insuring maximum pressure efficiency within the system under undue conditions of heat, such as those occasioned by fire; to provide for constant supervision of the continuity of the detector piping system and portions of the wiring of the auxiliary alarm circuit in such manner that the signal transmitted upon the rupture of the piping will be distinctive from the alarm transmitted upon the actuation of the system by fire, and further to provide most effective and certain service for insuring prompt transmission of a true fire alarm signal to suitable supervising authorities in the event of the occurrence of fire.

Other objects of the present invention will 85 become apparent to those skilled in the art from the following description taken in conjunction with the accompanying drawings wherein is diagrammatically illustrated an embodiment of the invention.

Figure 1 is a general diagrammatic view; and Fig. 2 is a detail of the illustrated pressure-responsive device.

In the illustrative embodiment of the invention herein shown is provided in general 95 a fire alarm telegraph system comprising the potentially active transmitter T, and a suitable signaling circuit therefor including the central station recorder R. Auxiliary boxes or signal initiators, A, are distributed 100 throughout the area, such auxiliary boxes being arranged in a local auxiliary circuit normally energized and including means manually restraining the transmitter T, adapted when the auxiliary boxes are actuated to condition the master transmitter T for 105

fire alarm signaling operation, the arrangement providing for partial operation of said transmitter T to transmit telegraphically a trouble signal in the event of a mere break of the auxiliary circuit.

- 5 The heat detecting system shown in general comprises a pressure-responsive device P and a piping system, p connected therewith, extending throughout the whole or 10 part of the protected area, so arranged that under certain conditions of heat the medium within the piping connections occasions a change of pressure in the responsive device, P, sufficient to actuate such device to do 15 useful work. The detecting piping p is constantly supervised as to its continuity by inclusion in a closed, energized circuit, and, preferably, as a part of the electric circuit in which the auxiliary boxes, A, are contained, so that supervision of the auxiliary 20 circuit constitutes supervision of the continuity of the heat detecting system. The arrangement provided is preferably such that in the event of deenergization of the 25 auxiliary circuit, as by the breaking of a wire or the failure of the source of current supply in said auxiliary system, the transmitter is caused to send a signal which is readily distinguishable from a true fire 30 alarm. Furthermore, the association of the systems is such that the control of the properly constituted fire alarm initiating devices is absolute and occasions the transmission of a desired true fire alarm.
- 35 Referring now to the specific showing of the drawing, the transmitter T is diagrammatically shown as a clockwork box of the normally-wound type, typifying any potentially-active transmitter, involving a number wheel, 10, for occasioning a plural-impulse signal several times repeated, said wheel preferably having between the first and second number, or tooth series, a projection, 11, and the wheel coacting with the 40 normally closed circuit-breaking switch 12. A controlling wheel 13 is provided with two peripheral notches, 13'—13'', and is arranged to rotate coincidentally with the rotation of the wheel 10, and is also arranged 45 to be normally locked against movement by engagement of a lever 14 with the notch 13'. 15 indicates a transmitter-controlling electromagnet, the armature whereof is carried by lever 14, so that the transmitter is restrained only while the electro-responsive magnet is energized. A switch-controlling arm 17 is provided to rotate coincidentally 50 with the wheel 13, and is arranged in respect to two circuit-making switches, 18 and 19, to close them both just as the second notch 13'' of the wheel 13 comes into position for engagement with the lever 14, and then to pass by such switches if the armature 55 remains free.
- 60 The switch 12 normally closes a telegraph 65

signaling circuit 20, including a source of current supply such as a battery 21, and the recorder R of any usual or desired type.

The heat detecting signal initiating system may be of any desired structure involving piping extending throughout the protected area and responsive means actuated to do useful work by changes of pressure in the piping due to sudden or dangerous heat. In the heat detecting system herein shown, 75 the pressure-responsive device P may conveniently comprise a receptacle 25, having one face formed by a diaphragm 26, provided with small vent openings 27, arranged merely to permit slow passage of air into or out of the receptacle to compensate for gradual changes in temperature and barometric pressure, but arranged to bulge outwardly and have its orifice closed upon a sudden increase of pressure within the receptacle 80 25. Constructions subserving this end are many and will readily occur to those skilled in the art, but the showing discloses a highly sensitive organization for the purpose, in which the diaphragm 26 is underlain by a second diaphragm 28 having therein an orifice 29 preferably non-registering with the orifice 27 in the outer diaphragm, so that the air passage through the two diaphragms is somewhat tortuous, and sensitivity is further increased by the provision of a loose paper disk or washer, 30, interposed between the two diaphragms. Obviously slow and gradual increases and 85 decreases of pressure within the receptacle 25 above or below atmospheric pressure result in the slow passage of air through the tortuous passage provided through the diaphragm valve thus provided, without occasioning movement of the diaphragms, but 90 a comparatively sudden or violent increase in pressure within the receptacle, such as is occasioned by a sudden rise in temperature due to fire, instantly affects the inner diaphragm and causes the paper washer to seat 95 against the orifice of the outer diaphragm, so sealing the relief way and causing the diaphragms to bulge outwardly together. Such movement of the diaphragms acts upon a lever 31, pivoted as at 32 upon the 100 casing, and preferably provided with an aperture-sealing disk 33 at such point that the outward pressure of the diaphragm 26 causes the vent aperture 27 to be sealed from the outside. Movements of the lever 31 are 105 utilized in doing work which will be hereafter described.

The heat detecting piping system, p, comprises a pipe which may be of very small diameter and correspondingly small bore, 115 extending throughout the area supervised, and preferably at both ends communicating with the receptacle 25, one extremity of the piping being electrically insulated as at 34 from the receptacle. The heat detecting 120

- piping p is preferably included as a part of the auxiliary circuit for the transmitter T normally controlling the electromagnet 15, and such circuit is maintained under test.
- 35 indicates a local source of current supply for the auxiliary circuit, connected to the auxiliary box A which preferably has for the purposes of the full embodiment of the present invention two sets of circuit-breaking switches 37 and 38, respectively, arranged for manual operation simultaneously to break the respective circuits, the switch 37 being connected in a wire 36 which leads from the battery 35 to the insulated end of the piping p , the normal auxiliary circuit thence continuing throughout the entire piping system and the shell of the pressure chamber 40 to the lower leaf of a normally closed circuit-breaking switch, 39, 20 which with a companion switch 39' is arranged to be opened by the elevation of lever 31. The upper leaf of such switch 39 is connected by wire 40 to binding post 15' of the controlling magnet 15 of the transmitter T , and from the other terminal 15'' of said magnet the circuit is connected back to the battery 35 through a wire 41.
- The switches 18 and 19 which are incorporated to form part of the circuit connections for telegraphic supervision of the auxiliary circuit and prevent the transmission of false alarm under certain conditions of operation of the system described, are connected as follows: The switch 18 is connected in a wire 47, which connects one leg of circuit 20 through the circuit breaker 38 of the auxiliary box A , and the switch 39' to magnet terminal 15', while the remaining switch 19 is connected in a wire 49, which 30 extends to and is connected with the binding post 15' of the transmitter-controlling magnet 15.
- It will be observed with respect to the heat-detecting system that slow rises or falls 45 in the pressure within the system due to normal changes in temperature or barometric pressure within the area protected occasion comparatively slow movements of the air to maintain the medium within the system, always at atmospheric pressure, the diaphragm valve arrangement serving to permit such "breathing" or passage of air to or from the system as is necessary to maintain the desired equilibrium of pressure 50 without the same. If, however, heat is applied to a portion of the detector piping system, as by the presence of a conflagration in the area protected, a sudden impulse of pressure is occasioned in the system which is 55 communicated to the diaphragm arrangement and instantly closes the relief orifice and causes the diaphragm arrangement to bulge outwardly, moving lever 31 and opening the switches 39 and 39'. This destroys 60 the continuity of the circuits for the controlling magnet 15 of the transmitter, thereby freeing the armature which is spring-retracted, and frees the transmitter motor for operation. As under such conditions nothing intervenes again to energize the 70 magnet 15 while the switches 39 and 39' are held open, the transmitter goes through its full cycle of operation and the wheel 10 operates upon the switch 12 to transmit its full round or complete signal to the recorder R 75 over the telegraph circuit 20. If, however, the rupture occurs in the auxiliary circuit alone, only a trouble alarm is transmitted. For example, in the event that the heat-detecting piping system p is ruptured at a 80 point marked X , the auxiliary circuit is interrupted and the relay 15 becomes deenergized, freeing the transmitter wheel for operation as heretofore described, but now when the wheel is rotated a third of its cycle 85 sending its number signal but once, the rise 11 of the wheel 10 breaks the circuit through the switch 12, and at the same time the operating arm 17 closes the switches 18 and 19, just as the second notch 13'' in the wheel 13 90 comes opposite the armature-carrying lever 14. Closure of the switches 18 and 19 occasions the energization of the magnet 15 from the battery 21 through a subsidiary or emergency circuit as follows: one line wire 95 20-47, (including 18, 38, and 39') 15-49 (including 19), other line wire 20, back to 21, so that the magnet 15, reenergized, attracts its armature and causes the lever 14 to engage the second notch of wheel 13, and thereby stop the activity of the transmitter T . Obviously, if either switch 38 or 39' be now actuated, it will break the transmitter-controlling subsidiary circuit and again free the transmitter for further operation to 100 transmit the balance of its signal, and either manual box A or the initiator of the heat detecting system will, when actuated, break such circuits, so that at the central station the receipt of the master-box signal once 105 only transmitted may be construed as a trouble signal, a receipt of said number twice or more transmitted may be construed as a fire alarm.
- In brief résumé it may be pointed out that 110 the present system provides (and such provision is believed to be new) a fire alarm telegraph system in which the master transmitter is controlled by an auxiliary circuit under test, and that the arrangement is such 115 that failure of the auxiliary test circuit may result in the transmission by the master transmitter of a trouble signal distinguishable from a true fire alarm signal, leaving the transmitter in condition for further 120 transmission of a true fire alarm in the event of further actuation. Further provision is made (and it is believed to be new) 125 of an atmospheric heat detecting system wherein the detector is at both ends open 130

to a pressure indicating device, and in such system is embodied also a structure permitting the normal maintenance of atmospheric pressure within the system but hermetically closing upon the sudden rise of pressure within the system to secure maximum efficiency in indicating sudden rise in pressure, such system further providing for the electrical supervision of the continuity of its 10 heat detecting piping as part of a circuit under test.

It will be apparent to those skilled in the art that numerous changes may be made in the system in its physical embodiments 15 without departure from the spirit and essence of the invention, and it will be understood that wide variations may be made from the specific embodiment herein by those skilled in the art in the application of the 20 teachings of this invention to different forms of heat detecting systems, telephone systems, and telegraph systems, heretofore known and hereafter evolved.

Having thus described my invention, 25 what I claim and desire to secure by Letters Patent is:

1. In a fire protection signaling system, a 30 telegraph system comprising a signal transmitter having a single signal wheel and a suitable circuit, and an auxiliary system comprising a local source of current supply, a circuit therefor, auxiliary boxes for varying the condition of said circuit to occasion the said transmitter to send by its 35 single wheel a true fire alarm, and means for occasioning said signal wheel to transmit in the signal circuit a signal distinctive from a true fire alarm upon rupture of said auxiliary circuit.

40 2. In a fire protection signaling system, a telegraph system comprising a potentially active signal transmitter having a single signal wheel, adapted for partial operation to transmit one signal and for other operation to transmit a distinguishable fire alarm, an auxiliary system normally energized and containing means for normally restraining the transmitter from operation, circuit 45 breaking signal initiating means for releasing said restraining means to permit the transmitter to effect its fire alarm operation, and means controlled by the transmitter and the signal initiating means for limiting the operation of the transmitter to a 50 partial operation upon the break of the normally energized auxiliary circuit, said means being disabled by the circuit breaking operation of the signal initiating means.

3. In a fire protecting signaling system, a 55 potentially active master signal transmitter, a circuit therefor, a source of current supply for said circuit and a signal receiving mechanism, the said transmitter providing a controlling magnet arranged when energized 60 to restrain the transmitter against opera-

tion, and signaling mechanism to transmit one character of signal when partly operated, and a different signal when fully operated, a locally energized normally closed circuit, including said transmitter-controlling magnet, means automatically operable upon the deenergization of said normally closed circuit for establishing a subsidiary circuit energized from a different source of current supply through said transmitter-controlling magnet after a partial operation of the signal wheel, and signal initiating auxiliary boxes including switching mechanism controlling both such circuits by which the transmitter-controlling magnet may be 70 energized. 75

4. In a fire protection signaling system, a signaling circuit including a source of current supply, a signal-receiving device, and a potentially active master transmitter comprising signaling mechanism, adapted to transmit one signal when partially operated and a different signal when fully operated, a controlling magnet, means for restraining or stopping said transmitter when the magnet is energized, a normally energized local circuit for said magnet, a subsidiary circuit for said magnet, normally deenergized; means for causing the energization of said subsidiary circuit in the event of a break in the normally energized circuit, and signaling means for breaking both the normally energized and the subsidiary circuit cotemporaneously. 85

5. In a fire protection signaling system, a potentially active signal transmitter, a suitable signaling circuit therefor, means for controlling the operation of said transmitter comprising an electromagnet adapted to restrain or stop the transmitter when energized, two independent sources of current supply for said electromagnet, a normal circuit, normally closed; including one source of current supply and the transmitter-controlling magnet, a subsidiary circuit, source 100 of current supply and the electromagnet, subsidiary circuit connections, normally open, for connecting the electromagnet with the source of current supply for the signaling circuit, and means for automatically closing said open circuit connection after a partial operation of the transmitter in the event of rupture of the normally closed circuit only. 105

6. In a fire protection signaling system, 110 a master transmitter potentially active, a suitable energized signal circuit therefor, a controlling magnet arranged when energized to restrain or stop the activity of the transmitter, a normally closed locally energized circuit for said magnet, subsidiary circuit connections for said electromagnet, normally open, and adapted when closed to connect said electromagnet for energization by the source of energy of the signaling cir- 115 120 125 130

- 5 unit, means for closing the normal opening of said circuit connections when the transmitter has effected a partial operation, a transmitter signal-initiating means comprising switching mechanism arranged to break both the normal and subsidiary circuit connections.
- 10 7. In a fire protection signaling system, a potentially active signal transmitter, a suitable signaling circuit therefor, means for controlling the operation of said transmitter comprising an electromagnet adapted to restrain or stop the transmitter when energized, two independent sources of current supply for said electromagnet, a normal circuit normally closed, including one source of current supply and the transmitter controlling magnet, a subsidiary circuit, normally open, including the other source of current supply, and said electromagnet, means for automatically closing said subsidiary circuit in the event of a break in the normally closed circuit, and means for 20 cotemporaneously breaking both the normal and subsidiary circuits.
- 15 8. In a fire protection signaling system, a potentially active transmitter, a suitable signaling circuit therefor, controlling means for said transmitter comprising an electromagnet adapted when energized to restrain or stop the transmitter, a normal circuit for said magnet including a source of current supply, a normally open subsidiary circuit for said transmitter including an independent source of current supply, means for automatically closing said subsidiary circuit in event of rupture in the normal circuit, means for initiating a signal when said subsidiary circuit is closed, and means for releasing the transmitter comprising the switching mechanism for cotemporaneously breaking the normal and subsidiary circuits for the transmitter-controlling magnet.
- 25 9. In a fire protection signaling system, the combination of a signaling circuit, a transmitter therein, a controlling magnet for the transmitter, an auxiliary circuit for the controlling magnet operatively engaging said magnet, another circuit for said magnet, normally open, and means to close said other circuit for said magnet to again energize it upon rupture of the said auxiliary circuit.
- 30 10. In a fire protection signaling system, the combination of a signaling circuit, a transmitter therein, a controlling magnet for the transmitter, an auxiliary circuit for operatively energizing the controlling magnet, and means controlled by the transmitter to establish another circuit for operatively energizing said magnet upon rupture of the said auxiliary circuit.
- 35 11. In a fire protection signaling system, the combination of a signaling circuit including a main battery, a transmitter there-
- in, a controlling magnet for the transmitter, an auxiliary circuit provided with a source of current supply, and means controlled by the transmitter to establish another circuit for the said magnet, including the main battery, upon rupture of the auxiliary circuit.
- 40 12. In a fire protection signaling system, a heat detecting system comprising piping extending throughout an area to be protected, and containing heat expansive fluid under atmospheric pressure, means subject to pressure in the pipe for initiating a signal upon rapid increase of pressure within the pipe, and means for affording communication between the pipe and the outer air, arranged for the relief of slow increase or decrease of pressure within the piping, and for closure upon the sudden increase of pressure within the piping.
- 45 13. In a fire protection signaling system, a heat detecting system comprising piping extending throughout an area to be protected, a pressure-responsive apparatus communicating therewith comprising a diaphragm provided with a vent open to the atmosphere when the diaphragm is under normal stress, means for closing said aperture upon sudden increase in pressure within the responsive device, and means associated with said diaphragm for initiating a signal upon movement of said diaphragm under suddenly increased pressure.
- 50 14. In a fire protection signaling system, a heat detecting system comprising piping extending throughout the protected area, a part providing a vent for permitting slow balancing of pressure upon opposite sides thereof without change in its position, means for closing said vent upon sudden change of pressure within the piping, and means responsive to such change of pressure within the piping system for initiating an alarm.
- 55 15. In a fire protection signaling system, a heat detecting system comprising a piping extending throughout a protected area, a pressure chamber into which both ends of the piping open, the ends of the piping being insulated from each other, a normally closed electric circuit including said piping, and means for initiating a signal upon the rupture of said circuit.
- 60 16. In a fire protection signaling system, the combination of a transmitter, a signaling circuit therefor, an auxiliary circuit, operatively energized transmitter-controlling means in said circuit, means operating automatically to establish another circuit for operatively energizing said controlling means upon rupture of said auxiliary circuit, and heat-responsive means governing both said circuits for the controlling means.
- 65 17. In a fire protection signaling system, a heat detecting system comprising piping extending throughout the protected area, a

- responsive part movable under change of pressure due to the application of heat in the piping system, a potentially active signal transmitter, a suitable signaling circuit 5 therefor, means for controlling the operation of said signal transmitter comprising an electromagnet normally restraining the transmitter while energized, and normally included in an energized circuit comprising 10 a portion of the piping system, a normally open subsidiary circuit for energizing said magnet when closed, means for closing said subsidiary circuit upon the rupture of the normal circuit, and means associated with 15 the responsive part of the heat detecting system for operation upon movement of the said responsive part caused by application of heat to the piping system, arranged to disconnect said transmitter-controlling magnet 20 from all of its energizing circuits.
18. In a fire protection signaling system, the combination of a signaling circuit including a source of current supply, a transmitter therein, a controlling magnet for said 25 transmitter, a normally energized local auxiliary circuit for said magnet, subsidiary circuit connections for bridging said magnet across the signaling circuit, switching

means for controlling said subsidiary circuit connections operable by the transmitter, 30 and signal initiating means adapted for contemporaneous operation of the auxiliary and subsidiary circuits.

19. In a fire protection signaling system, a heat detecting system, comprising piping 35 extending throughout a protected area, and a responsive part movable under change of pressure due to application of heat to the piping system, and a normally closed and energized electric circuit including said piping, a circuit excluding said piping, a signal transmitter operatively associated with both said circuits, responsive to rupture of said piping-including circuit to initiate an alarm and responsive to rupture of both 40 said circuits to initiate a distinguishable alarm, and means controlled by said responsive part of the heat detecting system arranged to rupture both said circuits.

In testimony whereof I hereunto set my 50 hand in the presence of two witnesses.

JOHN ELDON SHEPHERD.
